Primary Examiner — Deanna L Fluegeman*(74) Attorney, Agent, or Firm* — Hamilton, Brook, Smith & Reynolds, P.C.(57) **CLAIM**

The ornamental design for a wearable electronic display, as shown and described.

DESCRIPTION

FIG. 1 is a perspective view of the wearable electronic display embodying the present design.

FIG. 2 is a front view of the wearable electronic display.

FIG. 3 is a rear view of the wearable electronic display.

FIG. 4 is a top view of the wearable electronic display.

FIG. 5 is a bottom view of the wearable electronic display. FIG. 6 is a left side view of the wearable electronic display; and,

FIG. 7 is a right side view of the wearable electronic display. The broken lines in the drawings illustrate portions of the wearable electronic display that form no part of the claimed design.
